UNITED STATES PATENT OFFICE.

GUSTAF N. HYPSE, OF OMAHA, NEBRASKA.

WHEELED CULTIVATOR.

No. 911,128.

Specification of Letters Patent.

Patented Feb. 2, 1909.

Application filed June 28, 1905. Serial No. 267,366.

To all whom it may concern:

Be it known that I, GUSTAF N. HYPSE, a citizen of the United States, residing at Omaha, in the county of Douglas and State of Nebraska, have invented certain new and useful Improvements in Wheeled Cultivators, of which the following is a specification.

My invention relates to cultivators of the wheeled type, and pertains more especially to that class of wheeled cultivators wherein the seat-bar is pivotally supported on the offset axle, but is connected at its forward end by tension links to the underlying pivoted plow-beams in such a manner that the weight of the operator, when in his seat, exerts lifting effect upon said plow-beams.

My invention has been designed more especially as an improvement upon the type of machine illustrated in Letters Patent to John McL. Wright, No. 622,096, granted March 28, 1899, and embodies the same fundamental principle of construction and operation as the cultivator forming the subject-matter of the aforesaid patent.

The general object of my invention is to improve and simplify cultivators of this type, more especially in the direction of increasing the effectiveness of the weight of the operator, and the degree of sensitiveness with which it may be applied, as a means for counterbalancing the weight of the plow-beams, and rendering the latter more easy of manipulation by the operator.

To this and other minor ends my invention consists in an improved wheeled cultivator having the novel features of construction and relative arrangement of coöperating parts substantially as hereinafter described and more particularly pointed out in the claims.

My invention, in an approved mechanical form, is illustrated in the accompanying drawings, wherein,—

Figure 1 is a side elevational view, in partial perspective and with the near wheel removed, of my improved cultivator; Fig. 2 is a rear elevational perspective view of the same; and Fig. 3 is a top plan view. Fig. 4 is a detail view, partly in cross-section, showing the manner and means of pivoting the forward ends of the plow-beams.

Referring to the drawings, 5 designates the supporting wheels mounted upon the ends of a bowed or centrally offset axle 6. Secured to and suspended from the central horizontal member of the axle 6 by staples 7 is the inner end of a twin beam pole 8. Rig-

idly bolted to and between the beams of the pole is a depending inverted U-shaped yoke 9 preferably formed of angle iron, the vertical members of said yoke carrying at their lower ends laterally extending frames 10 constituting supports for the pivoted couplings of the forward ends of the plow-beams. These latter are designated by 11, and they are each pivotally mounted in the frame 10 with capacity for both vertical and horizontal movement by means of a pair of clamps 12 rigidly secured to the forward end of the plow-beam, said clamps 12 being pivotally mounted on horizontal pintles 13 that project laterally from the outer sides of a pair of inner clamps 14 which embrace a vertical pivot-bolt 15 mounted in the frame 10, all as clearly shown in Fig. 4.

The upper and lower horizontal members 75 of the frames 10 are provided with a plurality of apertures 10^a, whereby by shifting the pivot-bolt 15 the forward ends of the plow-beams may be adjustably mounted laterally of the frame so as to secure the desired separation of the plows or shovels on opposite sides of the row. To the rear ends of the plow-beams 11 are secured the usual handles 16 and shovel shanks 17. Diagonal braces 18 connect the vertical members 9 of the front yoke with the twin beams of the pole 8 to increase the rigidity of the connection between said yoke and pole.

Pivotally connected to the outer end of the lower horizontal member of each of the frames 10 are three frame bars, one designated by 19, extending vertically, the intermediate bar designated by 20, extending obliquely to and connected with the intermediate horizontal member of the axle just inside the bend, and third, designated by 21 extending rearwardly and adjustably connected to the axle just inside of the wheels 5, such adjustment being effected by a bolt 22 of a clamp mounted on the axle engaging any one 100 of a series of apertures 23 formed in said bar.

The vertical members 19 are the parts of the frame to which the hitch of the team is made through a hole 24; and the upper ends of said bars are connected with each other 105 through a transverse equalizer bar 25 pivotally connected centrally thereof to a bar 26 that extends rearwardly and is connected to the center of the horizontal member of the offset portion of the axle, and links 27 connecting the upper ends of the bars 19 with the ends of the equalizer bar 25.

28 designates a seat-bar which is pivotally mounted as by a transverse pivot-bolt 29 in a saddle 30 clamped upon the offset axle centrally thereof. The rear end of said bar is 5 downwardly offset a slight distance and provided with an operator's seat 31; while the forward end of said bar has pivotally mounted thereon a transverse equalizer bar 32, the ends of which are adjustably connected 10 by depending chains 33 with the forward ends of the plow-beams, the lower ends of said chains having hooks 34 adapted to engage any one of a series of eyes 35 formed in castings 36 bolted to the ends of the plow- 15 beams.

As seen in Fig. 2 the ends of the equalizer bar 32 are provided with a plurality of chain-engaging apertures to accommodate the lateral adjustment of the forward ends of the 20 plow-beams in the frames 10.

To the under sides of the plow-beams are swiveled stirrups 37; while rings 38 attached to the upper sides of said plow-beams are adapted to engage hooks 39 depending 25 from the inner ends of the pole, which support the plow-beams in elevated position out of contact with the ground when traveling to and from the field of operation.

The bent portion 6 of the axle is always inclined 30 forwardly of the vertical plane of the wheel-spindles, the degree of angularity being determined by the adjustable connection of the side-bars 21 with the axle, according to the weight of the operator, the heavier the 35 operator the greater being the angle of inclination of the axle from the vertical, and vice versa, in order to properly balance the machine. Similarly, the desired lifting effect on the plow-beams is obtained, according to 40 the weight of the operator, by connecting the hooks 34 to the proper eyes 35 longitudinally of the plow-beams; said hooks being connected in the rearmost eyes for the lightest operators, and in the foremost eyes for the 45 heaviest operators. It will also be observed that the apparatus as described and shown effects a perfect balancing of the plow-beams by the weight of the operator, without requiring the use of springs, ratchets, gears, 50 etc., such as are at present extensively employed for this purpose.

In the operation of the cultivator, the operator is able to nicely regulate the downward pressure upon the plows or shovels by 55 the relative amounts of pressure applied through the seat 31 and the stirrups 37, respectively. By means of the equalizer bar 32 and the seat-bar he also has perfect control over the vertical, as well as the lateral movements of the plows, being able to swing either 60 independently without affecting the other;

since the raising of either plow, through the increased downward pressure upon the seat 31 occasioned thereby, is accompanied by an elevation of the fulcrum of the equalizer 65 bar to an extent that offsets the downward movement of the opposite end of the equalizer bar connected to the opposite plow. The connection of the stirrups to the plow-beam instead of to the seat-bar enables the plows 70 to be largely controlled by the feet and legs of the operator instead of by his hands and arms.

While I have herein shown the plow-beams as of iron, and of skeleton form, it will be understood that wooden or other forms of 75 beams may be employed.

I claim:

1. In a wheeled cultivator, the combination with a centrally offset axle and a twin-beam pole connected thereto at its inner end, of a depending inverted U-shaped yoke the vertical sides of which are bolted directly to the beams of said pole, plow-beams pivotally connected at their forward ends to the lower 80 ends of the sides of said yoke, a seat-bar pivotally mounted on the offset band of the axle and having a seat at its rear end, and connections between the forward end of said seat-bar and said plow-beams, substantially 85 as described.

2. In a wheeled cultivator, the combination with an axle and a twin-beam pole connected thereto, of a depending yoke directly connected to said pole, the sides of said yoke 90 having pivot-supports extending laterally thereof, plow-beams mounted in said pivot-supports with capacity for both vertical and lateral swing, uprights adapted to receive the hitch of the team mounted on the lower 95 ends of the sides of said yoke, an equalizer-bar, a draft-bar connecting the latter centrally with the axle, and links connecting the ends of said equalizer-bar with the upper 100 ends of said uprights, substantially as described.

3. In a wheeled cultivator, the combination with a centrally offset axle and a pole connected thereto, of a depending yoke directly connected to said pole, the sides of 110 said yoke having pivot-supporting frames extending laterally thereof, plow-beams mounted in said frames on vertical and horizontal pivots, and frame-bars extending from the lower sides of said pivot-supporting 115 frames and connected directly to the horizontal hub and intermediate portions of the axle, respectively, substantially as described.

GUSTAF N. HYPPSE.
